US0D1044540S

(12) **United States Design Patent** (10) **Patent No.:** **US D1,044,540 S**
(45) **Date of Patent:** **** Oct. 1, 2024**

(54) **PERSONAL TRACKING DEVICE**

(71) Applicant: **Iowise Technologies, Inc.**, Austin, TX (US)

(72) Inventors: **Douglas Schulz**, Beaumont, TX (US); **Thomas Stith**, Houston, TX (US)

(73) Assignee: **IOWISE TECHNOLOGIES, INC.**, Austin, TX (US)

(**) Term: **15 Years**

(21) Appl. No.: **29/912,313**

(22) Filed: **Sep. 16, 2023**

CLAIM

The ornamental design for a personal tracking device, as shown and described.

DESCRIPTION

FIG. 1 is a top, left, front perspective view of the personal tracking device.

FIG. 2 is a front view of the personal tracking device.

FIG. 3 is a back view of the personal tracking device.

FIG. 4 is a top view of the personal tracking device.

FIG. 5 is a bottom view of the personal tracking device.

FIG. 6 is a left view of the personal tracking device.

FIG. 7 is a right view of the personal tracking device; and,

FIG. 8 is a bottom, right, back perspective view of the personal tracking device.

The dashed lines are included for the purpose of illustrating portions of the personal tracking device and form no part of the claimed design.

1 Claim, 8 Drawing Sheets
